UNITED STATES PATENT OFFICE

162,936

DRESS OR LIKE ARTICLE OF FEMININE APPAREL

Leo M. Cooper, New York, N. Y.

Application January 6, 1950, Serial No. 7,046

Term of patent 3½ years

(Cl. D3—26)

To all whom it may concern:

Be it known that I, Leo M. Cooper, a citizen of the United States, residing at Borough of Manhattan, in the county of New York and State of New York, have invented a new, original, and ornamental Design for a Dress or Like Article of Feminine Apparel, of which the following is a specification, reference being had to the accompanying drawing, forming part thereof.

In the drawing

Fig. 1 is a front view of a dress showing my new design, with the collar points crossed over the lapel points; and

Fig. 2 is a front view of the dress shown in Fig. 1, but with the collar and lapel rearranged in such fashion that the lapel points cross over the collar points.

The back of the garment is conventional.

I claim:

The ornamental design for a dress or like article of feminine apparel, substantially as shown and described.

LEO M. COOPER.
